JOHN T. ROBINSON AND GEORGE E. GOODING, OF BOSTON, MASSACHUSETTS; SAID GOODING ASSIGNOR TO SAID ROBINSON.

SAFETY DEVICE FOR BOX-ENDING MACHINES AND LIKE PRESSES.

1,329,431.

Specification of Letters Patent.

Patented Feb. 3, 1920.

Application filed July 25, 1918. Serial No. 246,680.

To all whom it may concern:

Be it known that we, JOHN T. ROBINSON and GEORGE E. GOODING, both citizens of the United States, residing at Boston, 5 county of Suffolk, State of Massachusetts, have invented a certain new and useful Improvement in Safety Devices for Box-Ending Machines and like Presses, of which the following is a specification, reference being had therein to the accompanying drawings.

The present invention relates to safety devices for box ending machines and like presses. As is well known to those skilled 15 in the art, operators on box ending machines and similar presses, frequently have their fingers crushed or damaged by getting them between the box form and the platen or head. Attempts have heretofore been 20 made to provide safety devices to prevent such accidents and which operate by stopping the machine in case the operator's finger is interposed between the box form and the platen. Such devices have not been 25 successful for various reasons, chiefly because of the difficulty of stopping a heavy rapidly moving machine, in the time permitted by the circumstances, and secondly, because such devices usually interfere to 30 some extent with the operative's freedom of action in running the machine. As is well understood by those skilled in the art, operatives will remove safety devices from machines and run the machine in a dangerous 35 unprotected condition rather than allow their earnings to be reduced or their convenience to be interfered with by a safety device.

The present invention has for its object 40 a safety device for box enders and similar presses which does not stop the machine but renders the pressing members inoperative and furthermore to provide a safety device which shall not interfere in the slightest 45 degree with the operative's freedom of movement. To this end the invention consists in providing mechanism by which one or the other of the press members is rendered freely yielding whenever anything is 50 interposed between the press members. After the press member has been rendered freely yielding sufficient pressure cannot be exerted by the other press member to injure the operator's finger. To render the 55 freely movable press member rigid to re-

sist the action of the moving press member, a slide moved in time with one of the press members is provided, and is so arranged that whenever the coöperating press member is displaced the slide cannot be 60 moved into position to support the freely movable press member. In other words, the displacement of the freely yielding press member prevents the support for said member which is moved in time with the machine being moved into position to perform its function of support. By this mechanism, it is not necessary to stop the machine in case the operative's finger gets in the way, since the auxiliary press or platen 70 being then freely movable and unsupported offers practically no resistance.

While the invention is described herein in connection with a box ending machine, it will be understood that it is applicable 75 to other forms of presses; furthermore the invention is not limited to its application to a press one member of which only is movable, since it is equally applicable to presses in which both members move. 80

The invention will be fully understood by reference to the following specification, taken in connection with the accompanying drawings, and the novel features thereof will be pointed out and clearly defined in 85 the claims at the close of this specification.

In the drawings, Figure 1 is a front view of a box ending machine embodying my invention.

Fig. 2 is a vertical section of the machine 90 shown in Fig. 1.

Fig. 3 is a front elevation of the top of the machine, showing the parts in the position occupied by them during the pressing operation.

Fig. 4 is a similar view showing the action of the machine in case the operator's finger is interposed between the box form and the freely movable press member.

Fig. 5 is a front view of the machine embodying our invention in modified form.

Referring to the drawings, at 11 is shown the frame of the machine. On the upper part of the frame of the machine, is supported a cross head or platen 12 which in 105 the type of press shown in the drawings, furnishes a relatively immovable member or abutment against which the movable press member or box form 13 operates. The box form is carried on a ram 15 operated by 110

mechanism which it is not necessary to describe herein. It will be understood that the body of the box is placed about the box form 13 and the box end is positioned underneath the platen after which the ram rises and unites the two parts of the box by subjecting them to heavy pressure.

At 16 is shown a second press member which is freely movable except when the box form has reached a point nearer the said freely movable press member than the thickness of a finger. The freely movable press member is provided with trunnions 17, each engaging a sliding block 18 vertically movable in slots 19 formed in the frame of the machine. This permits the member 16 to be moved vertically or to be tilted or rocked. The member 16 may be counterweighted by means of weights 20 connected to it by chains or other flexible connections 21, running over pulleys 22. The object of the counterbalancing of the member 16 is to make it freely yielding so that a touch on the underside will displace it vertically. If this counterbalancing were not provided, the operator's finger might be injured as the inertia of the platen, especially if the freely movable member be of large area and heavy construction might be enough to offer sufficient resistance to injure the operator's finger.

Between the freely movable press member 16 and the cross head or fixed press member 12 is placed a slide or support 23 movable horizontally in time with the machine by means of a bell crank 24, pivoted at 25 and having a fork 26 engaging a block 27 pivoted to lugs 28 on the upper side of the slide 23. The bell crank 24 is connected to one end of a connecting rod 29 the other end of which is attached to a cam lever 30. The cam lever 30 is provided with a cam follower 31. On the main driving shaft 32 of the machine is a cam 33 which acts on the cam follower 31. At 34 is shown a spring, one end of which engages a collar 35 on the connecting rod 29 and the other end of which rests on an abutment 36 on the frame of the machine.

The mechanism just described is such that when the roll 31 drops off the high point of the cam 33, the spring 34 causes the bell crank 24 to move the slide 23 to the left as shown in Fig. 1. This mechanism causes the slide 23 to be moved in time with the movement of the ram.

On the upper side of the freely movable press member 16 and on the underside of the slide or support 23 are located co-operating projections 37 and 38, there being spaces between the said projections sufficient to permit the projections of the other member to enter. The projections on the side of each member are finished as shown at 39 while the projections on the other member

are cut away slightly as shown at 40 thereby forming a line contact when the sides of the projections are in contact as shown in Fig. 4. This is for the purpose of reducing the friction, when the surfaces come together, to the lowest possible amount.

The machine embodying our invention operates in the following manner:

As the main shaft rotates and moves up the ram 15 and box form 13, the cam 33 revolves. When the box form has reached a position close to the underside of the freely movable member 16 but not close enough to cause the paper box to contact with the said member, the cam roll 31 drops off the high point of the cam 33 and the spring 34 moves the slide 23 to the left, as shown in Fig. 1. This movement of the slide is very slight being only a little more than the width of the top of the projections 37, 38. When the slide has been moved over, it occupies the position shown in Fig. 3, and at this time the corresponding members of the two sets of projections are in registration with each other so that the slide forms a support interposed between the freely movable press member 16 and the head 12. The pressing then takes place in the ordinary manner.

In case the operator's finger is between the box form and the underside of the freely movable press member, the operation of the machine is as follows:

The box form moves up until the operator's finger is brought into contact with the underside of the member 16. The further movement of the box form causes the operator's finger to lift the freely movable press member slightly. This takes place without causing any considerable pressure on the operator's finger because the member is carefully counterbalanced and freely yielding. The further upward movement of the box form causes the operator's fingers to lift up the freely movable press member. This takes place before the slide 23 has been moved to the left by the cam 33. When the projections 37 have been moved up so that their tops are above the lower faces of the projections on the underside of the slide the projections prevent the further movement of the slide into a position to resist the movement of the freely movable press member. During all this time the member 16 is freely movable and therefore no injury can be done to the operator's finger.

In Fig. 5 there is shown a slightly modified form of our invention. In that figure the freely movable press member is shown at 40 and is provided on its upper surface with projections 41. Between the cross head 42 and the freely movable member 40 is interposed a series of swinging projections 43, all actuated by a bar 44 on which is a pair of lugs 45 carrying a block 46 engaged by a forked arm 47 of a bell crank 48. Except

for the above described mechanism the structure of this device is exactly the same as that described in connection with Figs. 1 to 4 inclusive.

5 It will be seen that if the freely movable member 40 is displaced even very slightly, the swinging fingers 43 will be prevented from moving into position to support the freely movable member.

10 All the mechanism comprising our improved safety device in either of the forms shown may be easily concealed by a suitable housing and when so concealed the machine has practically the same appearance 15 as the machines which are not provided with safety devices. Furthermore, the operator has exactly as convenient access to the box form or press member as he has when no safety device is used. The safety device 20 does not hamper the operator in any way nor does it reduce the speed of the machine, or the operator's quickness of movement, and therefore there is no incentive for the operator to remove the safety device from the 25 machine or to tamper with it.

What we claim is:

1. In combination two press members, one of which is freely movable, counterweights for said freely movable press member, and 30 mechanism operated in time with the ma-

chine to render the said member immovable when the other of said press members has approached within a predetermined distance.

2. The improved box ending machine having a cross head, a ram, a press member between said ram and said cross head, counterweights acting on said member to render the same freely movable and mechanism operated by the ram to render said freely movable member immovable whenever the ram 40 has reached its predetermined position.

3. In combination, a cross head, a ram, actuating mechanism for the ram, a freely movable press member interposed between the ram and the cross head, a slide interposed between the freely movable press member and the cross head, a cam rotating with the ram actuating mechanism, a cam follower, connections between said cam follower and the said slide and a spring holding the cam follower in contact with the cam so that when the cam reaches a predetermined point the spring will actuate the connecting mechanism to interpose the slide between the freely movable member and the 50 cross head and render the slide immovable.

In testimony whereof we affix our signatures.

JOHN T. ROBINSON.
GEORGE E. GOODING.
